US00D921832S

(12) **United States Design Patent** (10) **Patent No.:** **US D921,832 S**
(45) **Date of Patent:** **** Jun. 8, 2021**

(54) **STORAGE CONTAINER FOR HIGH PRESSURE LIQUID OR GAS**

(71) Applicant: **THE JAPAN STEEL WORKS, LTD.,**
Tokyo (JP)

(72) Inventor: **Hironobu Arashima**, Muroran (JP)

(73) Assignee: **THE JAPAN STEEL WORKS, LTD.,**
Tokyo (JP)

(**) Term: **15 Years**

(21) Appl. No.: **35/507,453**

(22) Filed: **Feb. 28, 2019**

(80) **Hague Agreement Data**

Int. Filing Date: **Feb. 28, 2019**

Int. Reg. No.: **DM/202735**

Int. Reg. Date: **Feb. 28, 2019**

Int. Reg. Pub. Date: **Sep. 20, 2019**

(30) **Foreign Application Priority Data**

CLAIM

The ornamental design for a storage container for high pressure liquid or gas, as shown and described.

DESCRIPTION

2. Storage container for high pressure liquid or gas

2.1 : Front

2.2 : Back

2.3 : Right

2.4 : Left

2.5 : Top

2.6 : Bottom

2.7 : Cross sectional

2.8 : Perspective

2.9 : Perspective

2.10 : Enlarged view of 2.4

2.11 : Enlarged

2.12 : Enlarged

The dashed lines illustrate parts of the storage container that form not part of the claimed design. The dashed-dotted-dashed broken lines illustrate only the boundaries of the claimed parts and the disclaimed parts.

1 Claim, 12 Drawing Sheets
